CABINET DOOR

Nicholas A. Ungaro, Louisville, Ky., assignor to H. J. Scheirich Company

Filed June 19, 1969, Ser. No. 17,785

Term of patent 14 years

Int. Cl. D6—01

U.S. Cl. D33—1

FIG. 1

FIG. 2

FIG. 1 is a front elevation view of the cabinet door embodying my new design, and

FIG. 2 is a side elevation comprising an edge view of the door as seen from the left side of FIG. 1.

The essential features of my design reside in having the design characterized by the combination of a narrow vertical strip asymmetrically spaced on the cabinet door from the vertical edges of that door in conjunction with a wider and shorter horizontal strip laterally extending to the nearer vertical edge of that door and asymmetrically spaced from the horizontal edges of that door, all as shown.

I claim:

The ornamental design for a cabinet door, as shown.
